UNITED STATES PATENT OFFICE.

FRANK C. GUTEKUNST, OF KINTNERSVILLE, PENNSYLVANIA.

CALENDAR.

1,196,679.

Specification of Letters Patent. Patented Aug. 29, 1916.

Application filed May 1, 1915. Serial No. 25,232.

To all whom it may concern:

Be it known that I, FRANK C. GUTEKUNST, a citizen of the United States, residing at Kintnersville, in the county of Bucks and

5 State of Pennsylvania, have invented new and useful Improvements in Calendars, of which the following is a specification.

The invention relates to calendars, and more particularly to the class of perpetual 10 calendars.

The object of the invention is the provision of a calendar of this character wherein the same is of novel form so that the calendar matter is readily and easily adjusted for the changing thereof for keeping the said calendar up to date and accurate for perpetual use.

A further object of the invention is the provision of a calendar of this character 15 which is simple in construction, neat and attractive in appearance, readily and easily adjusted to render the same accurate, and also one which is inexpensive in manufacture.

25 With these and other objects in view, the invention consists in the construction, combination and arrangement of parts as will be hereinafter fully described, illustrated in the accompanying drawings, and pointed 30 out in the claim hereunto appended.

In the drawings:—Figure 1 is a plan view of my calendar, showing the front or door section open. Fig. 2 is a sectional view of Fig. 1, Fig. 3 is a perspective view of 35 another slide.

Similar reference characters indicate corresponding parts throughout the several views in the drawings.

40 My invention is adapted for use on any specific form of calendar of the perpetual calendar type.

It consists essentially in a rectangular shaped frame 10 preferably made from wood. In this frame will be mounted the 45 various moving parts of the calendar adapted to expose the desired calendar information for any determinate day and year. As these moving parts form no part of my present invention they will not be 50 described in detail.

I provide a simple means by which any

of the numerals indicated on the apron may be concealed so that attention may be directed in this manner to the particular date numeral concealed from view. Secured to 55 the sides of the frame are taut suspension wires 39 on which are detachably engaged the slide 41 which is formed of such a size as to completely cover any of the date numerals on the apron that may be exposed 60 to the opening 32. The side walls of the frame are each provided with a vertically spaced apart series of incut recesses in which the ends of the suspension wires 39 are secured so that the door section 65 may be closed without interfering with these suspension wires. A series of colored strips are also secured across the opening 32 at right angles to the suspension wires 39 so as to set apart a plurality of 70 outlines through which the particular numerals exposed through the opening 32 may be seen. The suspension wires 39 are spaced apart in such a manner as to permit the slide member 41 which may or may not 75 be slotted, sliding thereupon by means of its opposing beads. This slide member 41 has a bead turned around one of its edges adapted to slide upon one of said wires 39 and also has an inverted U-shaped bead 80 formed upon the opposite edge thereof, and adapted to slide upon another of said wires 39. In this way this slide member 41 may be raised and with its beads disengaging 85 themselves readily from the suspension wires that support them for it is evident owing to the fact that these suspension wires are mounted in the incut recesses in the sides of the frame that the slide member 41 cannot be slid endwise.

90 Numerous modifications may be resorted to in practice without interfering with the principle of my invention herein disclosed.

What is claimed is:

In a device of the class described in combination an open frame having opposing side walls, said side walls being each provided with a vertically spaced apart series of incut recesses, a series of longitudinal rigid rods secured in said recesses and 100 spaced from the outer frame thereof, a slide member constructed of sheet metal and hav-

ing an opening upon its main body portion, a bead turned around one of the edges of said member and adapted to slide upon one of said rods, and an inverted U-shaped bead 5 formed upon the opposite edge of said slide member and adapted to slide upon another of said rods.

Copies of this patent may be obtained for five cents each, by addressing the "Commissioner of Patents, Washington, D. C."

In testimony whereof I affix my signature in presence of two witnesses.

FRANK C. GUTEKUNST.
